COP DOFFING AND TUBE DONNING MECHANISM FOR COP WINDING MACHINES

Wilhelm Reiners and Gustav Kahlisch, Gladbach-Rheydt, Germany, assignors to W. Schlafhorst & Co., Gladbach-Rheydt, Germany, a corporation of Germany

Application March 1, 1934, Serial No. 713,560
In Germany March 31, 1933

17 Claims. (Cl. 242—32)

This invention relates to cop winding machines in which the doffing of cops and/or the donning of cop tubes is effected in respect of a plurality of spindles simultaneously, sometimes all the spindles on one side of the machine. For this purpose various manual operations have heretofore been required, requiring a considerable amount of labour, particularly where the cops carry only a comparatively small amount of yarn, so that frequent changes of cops are required.

10 The object of the present invention is to avoid manual operation, and to effect all the requisite movements automatically, irrespective of whether the winding machine has full length spindles for the cop tubes or whether the tubes are held between pegs engaging only into their ends.

The invention includes also means whereby the doffed cops remain in engagement with holders which give them a movement for breaking the yarn, and adjustable means whereby the 20 thread guides are uncoupled from their actuating mechanism when the cops have been full wound, so that the thread guides return automatically to their initial positions, the rapid return movement of the thread guides to their initial position serving automatically to initiate movement of the device for doffing or releasing the cops and donning the empty tubes. A fly wheel or the like may be provided at a suitable part of the drive so that the spindles continue to revolve 25 after the drive has been declutched, causing the loose end of the yarn to become attached to the spindles. The number of revolutions made by the spindles under the influence of the fly wheel, and consequently the length of the thread wound 30 on the spindles, may be regulated by means of a brake device.

Several examples of apparatus according to the invention are shown in the annexed drawings.

40 Figs. 1 and 2 are diagrammatic views of one form of construction, Fig. 1 being a sectional view along one of the spindle stations with certain parts in elevation, and Fig. 2, a front view of the machine.

45 Fig. 3 is a plan view of the cop and tube carrier used in this example, with part of mechanism for actuating it.

Figs. 4 to 8 show an example in which the tubes are held between pegs, the machine having no full length spindles. Fig. 4 is a sectional view of the machine along one of the spindle stations with certain parts in elevation, showing the positioning of the elements during the winding operation.

55 Fig. 5 is a front view of Fig. 4.

Fig. 6 is a view corresponding to Fig. 4 showing the positioning of the parts preparatory to the doffing movement.

Fig. 7 is a front view of Fig. 6.

Fig. 8 is a view corresponding to Fig. 6 showing the completion of the doffing movement. 5

Figs. 9 and 10 show parts of a cop winding machine having a fly wheel for the purpose already indicated, Fig. 9 being a sectional view with certain parts in elevation and Fig. 10 a plan view thereof with certain parts in section. 10

In the drawings, 1 designates the spindles, 2 the cops, 3 the empty cop tubes, and X a carrier for the tubes and cops, of a kind which we have shown in earlier specifications. 4 designates thread guides arranged on a common carrier 5, 15 serving a plurality of spindles.

The spindles 1 are driven from a common shaft 6, by bevel wheels 7 and 8, and the thread guides 4 with their carrier 5 are moved by racks 9 and pinions 10 mounted on a common shaft 11 (Figs. 20 3, 4).

The carrier X operates to doff the cops and to receive empty cop tubes and don them.

In the machine shown in Figs. 1 and 2 the carrier X executes both the doffing and donning operation. It rests on one-armed levers 12, which are fixed to the reciprocating and rotatable racks 13 and rock with said rack through 90°. At their free ends the levers 12 carry rollers 14, on which the carrier X is movable transversely of the spindles, so that the frame of the carrier, shown in Fig. 3 is able to shift, after doffing, the extent required to allow empty cop tubes placed on it to be positioned in front of the spindles. 35

The reciprocating movement of the carrier is produced by the above mentioned racks 13 and toothed segments 15, the latter of which are fixed to a common shaft 16. The racks 13 slide in bearings in the frame of the machine. 40

The rocking of the racks 13 is effected by a crank 17, which is also fixed to the shaft 16, said crank carrying a roller 18 engaging a grooved drum 23. The latter is on a shaft 19 mounted at 21, 22 in the frame 20 of the machine. The groove machined in the periphery of the drum 23 has no lift at the part 24, which is parallel with the end faces of the drum, but it has a lift at the two adjoining parts 25 and 26, corresponding to the degree of movement to be given to the carrier X. The toothed segments 15, and thus the racks 13, with the carrier X, remain stationary while the roller 18 of the lever arm 17 is in the part 24 of the groove. When, however, the roller 55

18 enters the part 25 or 26, the carrier X is moved parallel to the spindles.

One of the members of a clutch 27 is also slideable but not rotatable on the drum shaft 19, and 5 coacts with a complementary member 28, which forms the hub of a worm wheel 29. The latter is not slideable on the shaft 19, but is free to rotate thereon. The worm wheel 29 meshes with a worm 30 fixed to a driving shaft 31 mounted 10 in the frame 20, 32.

On the drive shaft 31 there is a pulley 33 connected by a belt 34 to a clutch disc 35, which is mounted on the drive shaft 6 for the cop spindles (Figs. 1, 2).

15 Automatic movement of the carrier X for doffing the cops is effected in the following manner:

The clutch 27-28 remains disengaged, and the grooved drum remains stationary, while the cops 2 are being wound. The crank 17 with its roller 20 18 engages the part 24 of the groove in drum 23. As soon as the cops are fully wound the thread guide bar 5 is automatically returned to its initial position, Figs. 6 and 9, by means to be described fully hereinafter. This movement causes a pin 25 36 on the rack 9 (Figs. 1 and 3) to impinge against an arm 37 on a rod 39 mounted rotatably in the frame part 40. At the lower end of this rod 39 there is a nose 38 which releases a lever 42 from its locked position described below, 30 when the rod 39 is rocked. The rod 39 is held in the locked position (Figs. 1, 2 and 3) by a spring 49 (Figs. 1 and 2). On a shaft 41 (Figs. 1 and 3) rotatable in the frame of the machine there is a lever 42 which has a joint at 43. The 35 two parts of the lever are held in alignment with each other by a leaf spring 44, but the spring allows one part of the lever to be swung in one direction by the turning movement of elements 37, 39 and 38; in Fig. 3, the forward part 40 of lever 42 may rock downwardly, and in Fig. 2, to the right. The lever 42 is locked by a finger 45, as shown in Figs. 1, 2 and 3, during the winding of the cops, said finger being fixed to a connecting rod 46. The actuation of arm 37 by pin 36 45 causes the nose 38 to shift the movable part of lever 42 to the right (Fig. 2) against the action of spring 44 to exclude the locking effect of finger 45 thereon.

A clutch lever 47 is also fixed to the shaft 41, 50 and its fork engages the clutch member 27, which is acted on by a spring 48, shown in Fig. 1.

An upwardly directed lever 79 is pivoted at 18 to the frame part 40. This lever actuates slideable member 80 of a clutch 80, 81 (Fig. 2) and 55 also actuates the member 82 of a clutch 82, 83. Lastly it operates the driving clutch 35. The engagement and disengagement of the clutch 80, 81 throws into and out of operation known mechanism 84, 85 for reciprocating the thread guides 60 4. As shown in Fig. 2 all three clutches 80, 81; 82, 83; and 35 are engaged, so that the machine is in operation. A lever 94 engages at 93 (Figs. 2 and 3) the lever 79, said lever 94 when in engaged position resting with its notch 95 (see Fig. 65 3) against an angle piece 96 on the frame 20 of the machine. The lever is held in this position by a spring 97. When the cops are fully wound and the stop 77 (Figs. 1 and 3) on rack 9 strikes the lever 94, the latter is rocked to the unlocked 70 position of 95, 96. Consequently the lever 79, which actuates the three clutches, is moved by the spring 98 (see Fig. 2) to its disengaging position.

As a result of the disengagement of the clutch 75 82, 83 a chain 99 connected to the clutch mem-

ber 83 and to a spring 100 (Fig. 1) pulls a de-clutched heart eccentric 84 and with it a lever 85 to the position shown in Fig. 1, and the clutch 80, 81 of the heart eccentric is also disengaged. This movement also causes the rack 9 to be returned from its foremost position to its rearmost position shown in Figs. 6 and 8. At the same time the pin 36 on the racks 9 causes movements of the doffing device to be initiated automatically as previously described. As the spindle drive is stopped, owing to the rapid return of the thread guide to its initial position and the consequent disengagement of the driving clutch 35, the provision of suitable rotating masses, whether in the form of the operative parts or of specially provided fly wheels (Figs. 9 and 10), causes the spindles to continue to rotate a short while, so that the yarn, which has been wound in a steep helix on the surface of the cop during the return of the thread guide, is caused to make a few convolutions on the spindles, at the part 131, (Figs. 1, 3), where the yarn runs on. According to Figs. 9 and 10 a fly wheel 122 is arranged on the spindle drive shaft 6. An adjustable angle piece 123 is fixed to the thread guide bar 5. A rod 126 is slideable in two stationary bearings 124 and 125. This rod carries at one end a brake shoe 127, which can be pressed against the rim of the fly wheel 122. A sleeve 128 is also fixed on the rod 126, between the bearings 124 and 125. This sleeve carries a transverse pin 129. A coil spring 130 provided on the rod 126 between the sleeve 128 and the bearing 125 normally holds the brake shoe 127 away from the fly wheel 122. As soon as the thread guide bar 5 returns to its initial position and the thread guide 4 arrives opposite the part 131 of the spindles 1, the angle piece 123 abuts against the transverse pin 129 and the brake shoe 127 is pressed against the fly wheel 122, so that the spindle drive shaft 6 is stopped. The number of revolutions which the cop spindles make in order to take up a sufficient length of yarn is regulated by the position of the angle piece 123 on the thread guide bar 5, the pressure of the brake shoe 127 on the fly wheel 122 being regulated. Obviously, suitable rotating masses may be provided on other rotary members of the drive, for instance on or adjacent to the inner cone of the clutch 35 (Fig. 2), instead of providing one or more fly wheels, whilst a brake rim 50 may also be furnished for the above mentioned brake. The carrier X and its actuating mechanism are omitted in both Figs. 9 and 10. The springs 100 for rapidly returning the thread guide 4 with its bar 5, are in this construction not fixed to discs 104 on the shaft 11, as in Fig. 1, but they are attached to the thread guide bar 5 and to a stationary part 115 of the frame of the machine. The above described invention may also be advantageously applied to cop winding machines of a different construction.

To enable the carrier X to move from the initial position below the spindle plane to its operative position level with the spindles there is mounted on the previously mentioned shaft 19 shown in Figs. 1 and 2 a box cam 50 having a groove which is partly concentric and partly eccentric. Into this groove engages a roller 51 on a connecting rod 46, which is pivotally connected at its upper end to a crank 52. This crank is fixed to the rack 13 as by a key and keyway to permit a longitudinal shifting of the rack 13 therein but to prevent a relative rotation between 13 and 52. The connecting rod 46 is provided at its lower end with a fork 53, which engages into an an-

nular groove in the hub of the box cam 50. The connecting rod 46 is thus guided at the top by the wrist pin of the crank 52, and at the bottom by the fork 53 in the annular groove of the box cam.

5 When the shaft 18 is turned to rotate the cam 23 from the position shown in Fig. 1, after engagement of the clutch 27, 28, the connecting rod 46, if in engagement with the eccentric part of the cam groove, is moved and the crank 52 is 10 rocked. By means of the cranks 12 fixedly mounted on the racks 13 the carrier member X is then moved upwards to the operative or doffing position, or else it is moved in the opposite direction. The notches 54 (Figs. 2 and 3) in the carrier X engage behind the cops 2 when the carrier is lifted. On continued rotation of the box cam 23 the roller 18 on the lever 17 enters the ascending part 25 of the groove. This causes the toothed segment 15 to rock to the left so that the racks 13 and carrier X are moved outwards. All the 20 fully wound cops are stripped off the spindles and fall into a trough 55 underneath. The cops are then conveyed by an endless belt 56 to a receptacle not shown.

25 The carrier X with the empty cop tubes 3 must now be moved for a short distance transversely of the spindles so that the tubes are placed in line with the spindles. For this purpose a stationary arm 57 (Figs. 1, 2 and 3) is arranged on 30 the frame of the machine, the front end of which carries a roller 58. A bell crank 60, 61 (Fig. 3) is pivoted to a pin 59 on the carrier X, and a spring 62 is connected to the shorter arm of this lever, this spring being also anchored to the carrier. This spring tends to hold the lever 60, 61 in the position shown in Fig. 3, so that when the carrier X is lifted the longer arm 60 abuts against a roller 58 on the stationary lever 57. When the carrier X reaches its doffing position the double 40 armed lever 60, 61 is rocked to the left, owing to its position in relation to the roller 58, so that the pull on said lever is increased, with the result that when the notches 54 pass the tips of the spindles the carrier itself moves longitudinally to a stop 63 (Figs. 1 and 3). The stop 63 ensures that the carrier occupies the correct doffing position; the stop is not shown in Fig. 2.

At this time the crank arm 17 with the roller 18 leaves the ascending part of the groove 25 in 50 the drum 23 and enters the part 26 of the groove, so that the carrier X is moved towards the spindles and consequently the empty tubes are pushed onto the spindles.

The drum 23 continues to rotate and the roller 55 18 again enters the part 24 of the groove. First, however, the drum 23 rotates until the connecting rod 46 is moved downwards by the eccentric part of the groove in the box cam, and the carrier X moves from operative position to the position 60 shown in Figs. 1 and 2.

When the roller 51 on the rod 46 again enters the eccentric part of the cam groove and the connecting rod 46 begins to lift, the abutment 45 on the connecting rod strikes the lever 42, 65 rocks it upwards and thus with the aid of the shaft 41 and forked lever 47 disengages the clutch member 27 from the clutch member 28, so that rotation of shaft 18 and box cam 50, and further ascent of the connecting rod 46, are 70 stopped. The cop changing operation is finished. The operative attaches to the spindles such of the yarns as may be broken, and starts the machine again.

In the example shown in Figs. 4 to 8 the cops 75 are moved some distance outwards by means of

holders 73 on the carrier X, in order to release them by breaking the yarn. The spindles 1 serve to drive the cop tubes 3 but do not extend through the tubes.

On the front ends of the racks 13 there are 5 brackets 64 which support iron plates 64a forming bearings for poppets 65 which engage into the front ends of the cop tubes. The cop tubes are held in operative position in conventional manner by yielding pressure applied to the 10 poppets.

Holders 66 and 67 for the empty tubes are arranged on the carrier X. The latter is provided in front and at the rear with flanged bars 68, 69, the bar 69 having bearings 71 and 72 15 for a spindle 70 having thereon forked lever arms 73. The levers 73 are held in normal position by springs 74 disposed between them and the bar 69. When the carrier X is in the doffing position shown in Figs. 6 and 7 the forked levers 20 engage the stub spindles 1 behind the bases of the cop tubes 2.

The movements of the carrier X are all performed in exactly the same way as described with reference to Figs. 1 to 3. Thus, to release 25 the cops 2 the carrier is first moved outwards by the gear segment 15 and racks 13. A lever 75 is fixed to the spindle 70 so that when the carrier X, after being raised from the position shown in Figs. 4 and 5 to the position shown in Figs. 6 30 and 7, is moved forwards to doff the cops, the lever 75 is also moved and caused to strike a stop 76 fixed to the frame of the machine. The lever 75 and spindle 70 are consequently rocked, placing the lever in the position shown in Fig. 8. 35 This causes the fork 73 to become disengaged from the cops and removes the pressure on the poppets 65. The position of the fixed stop is such that prior to the lever 75 being rocked by the same, and consequently prior to the release of the cops, the ends of the yarn on the cops are broken, between the cops and the points where the yarn runs on, so that the cops are able to drop into the trough 55.

It has already been proposed to provide yarn-cutting devices adapted to sever the yarn, but the device here illustrated has the advantage of greater simplicity and of continuous reliability in action. The stop 76 may be adjustable on 40 the frame of the machine, to suit the nature of the yarn and its resistance to breakage.

Fixed poppets may be used in lieu of the slideable poppets 65, in which case the driving stub spindles 1 are slideable and connected with the racks 13 by driving forks.

For shifting the thread guides after each stroke 55 the following device is employed.

As previously mentioned, a number of angle iron members 5 carrying thread guides 4 are fixed to the racks 9. These racks 9 are slidably mounted in the frame of the machine, and mesh with wheels 10 fixed to a shaft 11. On the same shaft 11 there is a disc 101. Fixed to the periphery of this disc is a belt, rope, chain or the like 103. This belt 103 can be wound more or less on the periphery of the disc 101. The belt 103 is attached also to the rim of a disc 83 (Figs. 1 and 2) on the shaft 86 which rotates in the fork bearing of the lever 85. On the same shaft 86 there is mounted, between the forked bearing of lever 85, a worm wheel 87 meshing at the top with a worm 88. Worm 88 is fixed to a shaft 105. This shaft 105 is also revolvably mounted in another fork 106a and 106b of the lever 85. The ratchet wheel 89 is fixed to the 60 65 70 75 80 85 90 95 100 105 110 115 120 125 130 135 140 145 150 155 160 165 170 175 180 185 190 195 200 205 210 215 220 225 230 235 240 245 250 255 260 265 270 outer end of the shaft 105. Between said wheel and the bearing 106a—b, a double-armed lever 91, 91a is loose on the shaft 105. This lever carries at the end of its arm 91a a feed pawl 90, 5 which drives the ratchet wheel 89 by the throw of the double armed lever 91, 91a. The feed movement is effected in the following manner.

The lever 85 carries a roller 103, which rolls on the periphery of a cam 84. This cam 84 is 10 fixed to a shaft 109. On the same shaft 109 is a gear wheel 110, the hub 81 of which is a member of the hereinbefore mentioned clutch 80, 81. A lever 111 is pivotally mounted on the shaft 109 and is held against axial movement. 15 The lever carries, approximately at its centre, a pin 112 on which an intermediate gear wheel 113 is rotatable. This intermediate wheel 113 meshes with a gear wheel 110 on shaft 109, and also with a gear wheel 114 rotatable on shaft 6 20 and fixed to the clutch disc 35. The movement of the gear wheel 114 is thus transmitted through gear wheels 113 and 110 and through the clutch 80, 81 to the cam 84. By this means the lever 35 with its previously described actuating mechanism is moved up and down. The double-armed lever 91, 91a consequently takes part in this movement. The arm 91 of this double-armed lever consequently abuts at each stroke against a set-screw 92 arranged on the frame of the machine (Fig. 1). The arm 91 of the double armed lever 91, 91a abuts against the head of the screw 92, earlier or later according to the adjustment of the screw, and consequently the throw of the shaft 105 will vary. Owing to the pawl 90 being 30 pivoted to the upper end of the arm 91a, the pawl rotates the ratchet 89 to a greater or lesser extent. Inasmuch as the wheel 89 and the worm 88 are fixed to a common shaft 105, the worm 88 rotates the worm wheel 87 on shaft 40 40 86. The disc 83 is also fixed to this shaft 86, and is rotated to a certain extent when the clutch 82, 83 is engaged. The belt 103 is connected to this disc 83. Thus each rotary movement of the disc 87 is transmitted to the shaft 45 45 11. On this shaft 11 there is also mounted a disc 104, to which a belt 99 is connected. The belt 99 is subject to the pull of a spring 100, connected to a bracket 115, so that the disc 104 urges the thread guide racks 9 in the direction 50 50 indicated by the arrow a (Fig. 1).

In Fig. 1 the thread guides 4 and racks 9 are shown in operative position. On the racks 9 there are adjustable collars 116, with springs 117 55 which impinge against fixed stops 132 when the thread guides 4 return from their end position to their initial position opposite the parts 131 onto which the yarn runs, when the cops have been wound. The impact of the racks is cushioned by the springs 117.

The fork 102 (Figs. 1 and 2) serves to engage and disengage the clutch 82, 83. This fork is fixed at its lower end to a rod 118, and engages the clutch member 82. The rod 118 is guided in 65 a bearing 119 and is pivotally connected to the lever 79, so that it is moved backwards and forwards by said lever to engage and disengage the clutch 82, 83. The engagement of the clutch 82, 83 is effected by a compression spring 120 70 on shaft 86, said spring bearing against an adjustable collar 121 on said shaft 86. The disengaging of the clutch 82, 83 is effected by the thrust of lever 79, transmitted through rod 118 75 and forked lever 102.

We claim:

1. In a cop winding machine, a winding mechanism comprising a group of spindles, a movable member, and means for imparting to said member a progressive movement during the winding of a group of cops on said spindles; a doffing mechanism, normally inoperative power driving means for said doffing mechanism, and means controlled by said member, upon reaching a predetermined point in its progressive movement, for setting said doffing mechanism in operation by said driving means. 5

2. In a cop winding machine, a winding mechanism comprising a group of spindles, a thread guide mechanism cooperating therewith, means for imparting to said thread guide mechanism a progressive movement during the winding of a group of cops on said spindles; a doffing mechanism, normally inoperative power driving means for said doffing mechanism, and means controlled by said thread guide mechanism, upon reaching a predetermined point in its progressive movement, for setting said doffing mechanism in operation by said driving means. 10

20 3. In a cop winding machine, a movable member, and means for imparting to said member a progressive movement as the cops are wound; a winding mechanism comprising a row of spindles, a doffing unit normally out of the plane of said spindles, means for moving said doffing unit into the plane of said spindles and restoring the same to normal position; normally inoperative power driving means for operating said last-mentioned means; and means operated by said movable member, upon reaching a predetermined point in its progressive movement, for setting said doffing unit moving means in operation by said power driving means. 25

4. In a cop winding machine, a winding mechanism comprising a row of spindles; a movable member, and means for imparting to said member a progressive movement as the cops are wound; a doffing and donning unit cooperating with said spindles and comprising alternately arranged doffing devices and empty tube supports; operating means comprising means to move said unit outward for doffing cops, means to move said unit laterally to align the empty tubes on said supports with said spindles, and means to move said unit inward to don said tubes; normally inoperative power driving means for said operating means; and means controlled by said movable member, upon reaching a predetermined point in its progressive movement, for setting said operating means in operation by said power driving means. 40

45 5. In a cop winding machine, a winding mechanism comprising a row of spindles; a movable member, and means for imparting to said member a progressive movement as the cops are wound; a doffing and donning unit cooperating with said spindles and comprising alternately arranged doffing devices and empty tube supports; operating means comprising means to move said unit outward for doffing cops, camming means operative during said outward movement to shift said unit laterally to align the empty tubes on said supports with said spindles, and means to move said unit inward to don said tubes; normally inoperative power driving means for said operating means; and means controlled by said movable member, upon reaching a predetermined point in its progressive movement, for setting said operating means in operation by said power driving means. 50

55 6. In a cop winding machine, a winding mechanism comprising a row of spindles; a movable member, and means for imparting to said member a progressive movement as the cops are wound; a doffing and donning unit cooperating with said spindles and comprising alternately arranged doffing devices and empty tube supports; operating means comprising means to move said unit outward for doffing cops, camming means operative during said outward movement to shift said unit laterally to align the empty tubes on said supports with said spindles, and means to move said unit inward to don said tubes; normally inoperative power driving means for said operating means; and means controlled by said movable member, upon reaching a predetermined point in its progressive movement, for setting said operating means in operation by said power driving means. 60

65 7. In a cop winding machine, a winding mechanism comprising a row of spindles; a movable member, and means for imparting to said member a progressive movement as the cops are wound; a doffing and donning unit cooperating with said spindles and comprising alternately arranged doffing devices and empty tube supports; operating means comprising means to move said unit outward for doffing cops, camming means operative during said outward movement to shift said unit laterally to align the empty tubes on said supports with said spindles, and means to move said unit inward to don said tubes; normally inoperative power driving means for said operating means; and means controlled by said movable member, upon reaching a predetermined point in its progressive movement, for setting said operating means in operation by said power driving means. 70

75 8. In a cop winding machine, a winding mechanism comprising a row of spindles; a movable member, and means for imparting to said member a progressive movement as the cops are wound; a doffing and donning unit cooperating with said spindles and comprising alternately arranged doffing devices and empty tube supports; operating means comprising means to move said unit outward for doffing cops, camming means operative during said outward movement to shift said unit laterally to align the empty tubes on said supports with said spindles, and means to move said unit inward to don said tubes; normally inoperative power driving means for said operating means; and means controlled by said movable member, upon reaching a predetermined point in its progressive movement, for setting said operating means in operation by said power driving means. 75

6. In a cop winding machine, a winding mechanism comprising a group of relatively movable spindles and poppets adapted to hold cop tubes between them; a movable member, and means for imparting to said member a progressive movement as the cops are wound; a doffing mechanism comprising means to separate said spindles and poppets, means to engage the cop bottoms to hold them against said poppets until the threads break, and means to separate said engaging means from said poppets to release the cops; normally inoperative power driving means for said doffing mechanism; and means controlled by said movable member, upon reaching a predetermined point in its progressive movement, for setting said doffing mechanism in operation by said driving means.

7. In a cop winding machine, a winding mechanism comprising a group of spindles and a thread guide mechanism cooperating therewith, restoring means urging said thread guide mechanism toward an initial position, means for moving said thread guide mechanism progressively as the cops are wound, means operable by said thread guide mechanism upon reaching a predetermined point in its movement for releasing the same to the action of said restoring means, a doffing mechanism, normally inoperative power driving means therefor, and means controlled by said thread guide mechanism upon its movement toward initial position for setting said doffing mechanism in operation by said driving means.

8. In a cop winding machine, a winding mechanism comprising a group of spindles and a thread guide mechanism cooperating therewith, restoring means urging said thread guide mechanism toward an initial position, means for moving said thread guide mechanism progressively as the cops are wound, means operable by said thread guide mechanism upon reaching a predetermined point in its movement for releasing the same to the action of said restoring means, a doffing and donning unit comprising doffing devices and supports for empty cop tubes alternately arranged, operating means for imparting outward and inward doffing and donning movements to said unit, means for laterally shifting said unit from doffing to donning position, normally inoperative power driving means for said operating means, and means controlled by said thread guide mechanism upon its movement toward initial position for setting said operating means in motion by said driving means.

55 9. In a cop winding machine, a winding mechanism comprising spindles, driving means therefor, means to uncouple said spindles from said driving means, and weight means which remain connected to said spindles to continue their rotation after their disconnection from said driving means, said spindles having a base part on which the thread is wound by said continued rotation.

10. In a machine as described in claim 9, brake means adapted to limit said continued rotation of said spindles to a substantially definite number of turns.

11. In a cop winding machine, a winding mechanism comprising spindles each having a base part on which the thread can be wound, a thread guide mechanism comprising thread guides movable from an initial position opposite said base part to the winding limit of the cops mounted on said spindles, driving means for said spindles, means controlled by said thread guide

mechanism at the limit position of said thread guides to uncouple said spindles from said driving means, weight means which remain connected to said spindles to continue their rotation after their disconnection from said driving means, means to restore said thread guides to initial position to cause the thread to be wound upon said base part of the spindles before their rotation ceases.

12. In a cop winding machine as described in claim 11, brake means for stopping said spindles, and means movable by said thread guide mechanism to apply said brake means.

13. In a cop winding machine, means to support a cop comprising a spindle and poppet, said spindle having a base part on which the thread can be wound, a thread guide movable to position to wind the thread on said base part when the cop is wound, doffing means for separating said spindle and poppet to release the cop, and means for engaging the cop bottom to hold the cop nose against said poppet while said spindle and poppet are separated, whereby to sever the thread.

14. In a machine as described in claim 13, means operable by the movement of said separating means to disengage said engaging means from the cop bottom subsequent to the severing of the thread.

15. In a cop winding machine, a plurality of juxtaposed winding spindles; driving means therefor comprising a drive shaft; thread guides cooperating with said spindles; means operated by said driving means for reciprocating said thread guides in unison; a cop handling unit adjacent said spindles having thereon stripping faces associated with said spindles for stripping the finished cops therefrom, means for receiving the finished cops and means for supporting a plurality of juxtaposed empty cop tubes, said last-mentioned means lying in a plane displaced from the plane containing said winding spindles; means responsive to the return of said thread guides to their initial position for automatically actuating said cop handling unit in a direction

parallel to the axes of said spindles for stripping simultaneously the finished cops which comprises a normally disengaged clutch associated with said drive shaft, locking means for maintaining said clutch in disengaged position against a yielding force, tripping means for said locking means actuated by the return of said thread guides to their initial position to effect an engagement of said clutch, a cam drum driven by said drive shaft in the engaged position of said clutch, an actuating segment controlled by said drum, and a cylindrical gear rack in engagement with said segment and connected with said cop handling unit, a second cam driven by said drive shaft in the engaged position of said clutch, a crank non-rotatably mounted on said cylindrical gear rack, a connecting rod joined to said crank and controlled by said second cam to effect a movement of said cop handling unit transversely of the spindle axes to set the stripping faces in position for operation.

16. The combination claimed in claim 15 wherein the cam surfaces on the cam drum and the second cam are so shaped as to impart an upward movement to the cop handling unit by rocking said cylindrical gear rack, a forward and return longitudinal movement to said gear rack while the cop handling unit remains in its raised position, and a downward movement to the cop handling unit by reversely rocking said cylindrical gear rack.

17. The combination claimed in claim 15 wherein the cam surfaces on the cam drum and the second cam are so shaped as to impart an upward movement to the cop handling unit while the cylindrical gear rack remains stationary in a longitudinal direction, a forward and return longitudinal movement to said gear rack while the cop handling unit remains in its raised position, and a downward movement to the cop handling unit while the cylindrical gear rack remains stationary in a longitudinal direction, and

the locking means for maintaining said clutch in disengaged position comprises a yieldingly articulated arm, and a locking projection on said connecting rod cooperating with the portion of said articulated arm which is affected by said tripping means, said locking projection becoming effective at the termination of the movement of said connecting rod. 5
